UNITED STATES PATENT OFFICE

2,630,261

RAILWAY CAR LADDER

Karl F. Nystrom, Nashotah, Wis., assignor, by
mesne assignments, to International Steel
Company, Evansville, Ind., a corporation of
Indiana

Application June 16, 1949, Serial No. 99,471

2 Claims. (Cl. 228—49)

1

This invention relates to improvements in railway freight cars and more especially to the construction of ladders for the walls of said cars to afford a trainman easy access to the roofs of such cars.

The principal objects of the invention are to provide an improved railway freight car ladder which is of simple construction, easy and economic to manufacture, complies with all safety rules of the Interstate Commerce Commission and of the Association of American Railroads and is most readily removed from the car as a unit in case a tread thereof, for example, is in need of repair or replacement.

A further object of the invention is to provide a construction of ladder stile and ladder tread wherein the ends of said treads may be secured to said stiles by being passed through aligned holes in spaced parallel legs of said stiles and upset on both sides of said legs and holes to provide a very secure union of said treads to said stiles. This method of attaching the ladder tread to the stiles, which practically rivets the ends of the treads to the stiles, forms another object of the invention.

Other objects and advantages of the invention will appear in the following description thereof.

Referring now to the accompanying drawing forming part of this application and wherein like reference characters indicate like parts:

Fig. 1 is a fragmental side elevation of one corner of a railway house car showing a front elevation of one of my improved ladders attached to the side of the car, and showing a side elevation of one of said ladders attached to the end of said car;

Fig. 2 is an enlarged cross sectional view on line 2—2, Fig. 1, showing in elevation an end of a ladder tread upset on opposite sides of a leg of a ladder stile;

Fig. 3 is an enlarged perspective view of the upper end of a stile and bracket showing a portion of a ladder tread secured thereto.

In the drawings:

The side sheathing of the car is indicated at 10, the car side plate at 11, roof at 12 and end wall at 13.

The improved ladder is adapted for attachment to either the side and/or end of the car, substantially as shown in Figure 1. The ladder comprises a pair of spaced angle ladder stiles, each stile comprising legs 14 and 15. The stiles are arranged so that legs 15 extend in the same plane, which plane is parallel to the plane of the car

side or end when mounted thereon and with the legs 14 facing each other and in parallel planes at right angles to the plane of legs 15. Legs 14 are provided with a plurality of similarly spaced holes 16 which may be axially aligned so that a ladder tread 17 of substantially the same diameter as said holes 16 may have opposite ends thereof passed through a pair of said aligned holes, as indicated in dotted lines at 18, Fig. 2, and then the material of said treads on opposite sides of said stiles 14 gripped in jaws suitable for the purpose and electric current and pressure simultaneously applied thereto. Sufficient heat is generated by contact resistance to allow the pressure to upset the end portions of the tread on opposite sides of the legs 14, as shown at 19 in Fig. 2, and cause some fusion of the material with the edges of the hole, thereby practically riveting the ends of the tread to said legs of the ladder stiles.

The ladder thus formed is provided at each end of each stile with Z-shaped brackets, each of which comprises flanges 20 and 21, occurring in spaced parallel planes, and a web portion 22 extending at an incline from one flange to the other, the angles between the web and flanges being acute. Flanges 20 are riveted flatwise, as at 23, to the respective ends of the stiles and flanges 21 are provided with holes 24 for application therethrough of bolts or rivets 25 to secure the ladder structure to a car wall. The brackets just described are formed from strap material of a width substantially equal to the width of legs 15, and webs 22 extend over the ends of the stiles, contacting corners of the stiles 14 and are welded to said corners, as at 26. There is thus a triangular area, when the ladder is viewed in side elevation, between ends of legs 14 and the webs 22 affording a gusset section for increased strength.

I claim:

1. Mounting means for a ladder of the type comprising a pair of spaced angle stiles having legs extending in spaced parallel planes and co-extensive with portions extending coplanar with respect to each other and supporting ladder treads therebetween, consisting of a Z-shaped bracket individual to each end of each of the stiles, each Z-shaped bracket having a pair of flat ends interconnected by a laterally extending strip member where one flat end of each Z-shaped bracket is individually secured to each end of the coplanar portions of said angle stiles in a position in which said laterally extending strip member is spaced from the end of the stile

at the secured end thereof, and wherein the other flat end of each Z-shaped bracket serves as a fastening means with respect to a supporting wall surface, the said strip members having a width substantially corresponding to the width of the associated coplanar portions of said stiles and projecting rearwardly therefrom beyond the inner peripheral edges of the parallel extending legs of said stiles, the inner faces of said strip members at opposite ends of said stiles being limited in the selective positioning thereof in one direction by contact abutment with the inner corners of the ends of said parallel extending legs for forming an attachable support for the ladder.

2. Mounting means for a ladder of the type comprising a pair of spaced angle stiles having legs extending in spaced parallel planes and co-extensive with portions extending coplanar with respect to each other and supporting ladder treads therebetween, consisting of a bracket individual to each end of each of the stiles, each bracket having a pair of flat ends interconnected by a laterally extending strip member where one flat end of each bracket is individually secured to each end of the coplanar portions of said angle stiles in a position in which said laterally extending strip member is spaced from the end of the stile at the secured end thereof, and wherein the other flat end of each bracket serves as a fastening means with respect to a supporting wall surface, the said strip members having a width substantially corresponding to the width of the associated coplanar portions of said stiles and

10

5

projecting rearwardly therefrom beyond the inner peripheral edges of the parallel extending legs of said stiles, the inner faces of said laterally extending strip members at opposite ends of said stiles being limited in the selective positioning thereof in one direction by contact abutment with the inner corners of the ends of said parallel extending legs for forming an attachable support for the ladder.
